SHOE BUFFING MACHINE

Harold Ernest Elliott and Lawrence Mawbey,
Leicester, England, assignors to United Shoe
Machinery Corporation, Borough of Flemington,
N. J., a corporation of New Jersey

Application October 31, 1940, Serial No. 363,736
In Great Britain December 1, 1939

1 Claim. (Cl. 74—49)

This invention relates to shoe buffing machines and is herein illustrated and described as embodied in a buffing machine provided with a pair of bottom scouring rolls and a pair of shank buffing tools of the inflated disk type. In the illustrated machine, the shaft of the bottom scouring tools is arranged to be reciprocated axially, and all of the various tool shafts are driven by belts.

It is an object of the present invention to provide an improved machine of the type above referred to. In accordance with this object, the illustrated machine is provided with an improved mechanism for reciprocating the shaft of the bottom scouring rolls, such reciprocating mechanism being designed to avoid the transmission of transverse thrusts to the shaft.

The invention will be best understood from the following description of the preferred embodiment thereof selected for purposes of illustration and shown in the accompanying drawings, in which

Fig. 1 is a front elevation of the improved machine;

Fig. 2 is a side elevation of the improved machine;

Fig. 3 is a sectional view in side elevation of the portion of the machine associated with the bottom scouring rolls;

Fig. 4 is a sectional view taken in the plane of the axis of the bottom scouring roll shaft showing a portion of the mechanism for reciprocating the shaft; and

Fig. 5 is a detail view further illustrating said reciprocating mechanism.

The illustrative machine has a frame in the form of a casing comprising a base section 1 upon which is mounted an intermediate section 3 (Fig. 2) which supports a top section 5. The base section 1 has upright side walls, a front portion which slopes upwardly and rearwardly at a small angle to the vertical, and a rear portion which slopes upwardly and forwardly at a small angle to the vertical. The front and rear portions of the base section of the casing are provided with large openings, normally covered by plates, which may be readily removed from the casing to provide access to the interior thereof, the plate at the front of the machine being indicated by the reference numeral 7.

In the base section of the casing, at the right-hand side thereof, is mounted an electric motor 9 a portion of which extends into the interior of the casing through an opening 11 in the side walls of the base section 1. A driving shaft 13

of the motor is provided with a pulley 15 (within the casing) which drives, through a belt 17, a pulley 19 fast on a horizontal countershaft 21 extending transversely of the machine and journaled in three bearings supported by brackets extending upwardly from the bottom of the base section of the casing near to the rear thereof.

The intermediate section 3 of the casing is of general box-like structure and extends across at least substantially the full width of the base section. From a front wall 27 of this intermediate section extend in a forward direction three brackets 29, one of which is positioned at the left-hand end portion of the wall, one at the mid-portion of the wall and one at the right-hand end portion of the wall. Each of the brackets 29 is provided with a bearing in which is journaled a horizontally disposed shaft 31 extending transversely of the machine, on which shaft two scouring rolls 33 are mounted, one between the left-hand bearing and the middle bearing, and the other between the middle bearing and the right-hand bearing.

Sufficient space is provided between the end surfaces of the rolls 33 and the adjacent bearings to allow reciprocation of the shaft 31 through about $\frac{1}{8}$ of an inch by means hereinafter described, and, in the case of the right-hand roll, a pulley 35 (Fig. 2) is provided between the

right-hand roll and the right-hand bearing. The rolls are arranged to be driven, at a comparatively high speed, for example about 3500 R. P. M., from a pulley 37 on the countershaft 21 by means of a belt 39 which passes through an opening in the front portion of the base section 1. The portion of the belt 39 which lies outside the casing, together with the pulley 35, is shielded by a guard 41 secured to the casing. The shaft 31 is positioned by the brackets 29

some distance forwardly of the upper front portion of the base section 1 to allow clearance for the toe portion of a shoe when its sole is being scoured by one of the rolls. The left-hand end portion of the shaft 31 is shielded by a cap-like guard 43 secured to the left-hand end bracket 29.

Since the roll-carrying shaft is arranged not only to be rotated at a comparatively high speed, but also to have a reciprocatory movement imparted thereto as above referred to, it is important to provide adequate, but not excessive, lubrication of the bearings in which this shaft is journaled. The following arrangement has been found to provide satisfactory lubrication of said bearings. Each bearing comprises a cylindrical brass bushing 45 (Fig. 3) in which the roll-carry-

ing shaft is received and which is mounted in bores in end walls of the hollow portion 47 (Fig. 1) of the bracket 29. An inner surface of the bushing 45 has formed therein a "figure of 8" oil groove (not shown). An outer surface of the bushing 45 has a longitudinal T-shaped slot 49 formed therein, which communicates with the oil groove. Received in the slot 49 is a felt pad 51 which is supplied with oil by means of a wick 53 hung over the felt pad and having a portion dipping into oil 55 in an oil-reservoir formed by the hollow end portion 47 of the bracket 29. The bracket 29 is provided with a hinged cover 57 through which oil may be supplied to the reservoir. Each reservoir is provided with a small opening normally closed by a screw 59 through which opening the reservoir may be drained on removal of the screw.

To the rear of each roll there is a dust hood 61 (Fig. 3) which is connected, through a branch duct 60 and a main duct (not shown), to dust-collecting means comprising a fan housing 63 (Fig. 2) mounted in the front portion of the base section 1 of the casing, a fan within the housing being driven by belt drive 65 from a pulley 67 on the countershaft 21. The outlet of the fan housing may be connected to an exhaust conduit leading outside the building to a suitable dust-separator.

Below the scouring rolls (and common to both rolls) is a dust-collecting pan 69 of sheet metal which is connected by a duct 71 to the main duct above mentioned. Each scouring roll is provided with a spring-controlled cover 73 pivoted to the intermediate section 3 of the casing at 75. Since the duct 61 abuts against a lower surface 74 (Fig. 3) of the cover 73 when the latter is in operating position, and since the duct is in contact with a rear wall 76 of the pan 69, a very effective dust-removing arrangement results.

Fast on a shaft 76 (Fig. 2) journaled in bearings in a bracket 77 extending through an opening in the front portion of the base section 1, at the left-hand side thereof, is a brush 79 for removing the dust which accumulates on the shoes during the buffing operations. The bracket 77 is in the form of a guard and dust hood which partially surrounds the brush, and is secured to the base section 1. The shaft 76 is provided with a pulley 81 driven by belt 83 from a pulley on the countershaft 21. The belt 83 passes through an opening in the front portion of the base section 1, and a guard 87 is provided for the portion of the belt which extends through the opening just referred to.

The means for imparting reciprocatory movement as aforesaid to the shaft 31 will now be described. The shaft 31 has a short reduced end portion 89 (Fig. 4) about one and one-eighth inches long and extending to the right beyond the right-hand end wall of the right-hand bearing 29. A cylindrical sleeve or collar 91 (see also Fig. 5), having an internally directed cylindrical flange 93 at one of its end portions, surrounds the portion 89 of the shaft 31, the internal diameter of the flange 93 being slightly larger than the normal diameter of the shaft 31, while the internal diameter of the remainder of the sleeve 91 is considerably greater than the diameter of the reduced portion 89 of the shaft. This portion 89 is threaded for a distance of about one-half inch from the right-hand end of the shaft. An inner race 95 of a ball bearing is clamped on the portion 89 of the shaft between a shoulder 97 formed by the reduction in diameter of the

shaft, and nuts 99 threaded on the end portion of the shaft. The ball bearing has an outer race 101 of such a diameter as to be comfortably received within the sleeve 91, being clamped therein between the flange 93 and a cap 103 threaded into the end portion of the sleeve remote from said flange. It is evident that through the agency of the above-described ball bearing the sleeve or collar 91 is carried upon the shaft 31.

The sleeve 91 has two short cylindrical trunnion pins 105 extending outwardly from its outer surface in diametrically opposed directions. On each of the pins 105 is rotatably mounted a small block 107. The blocks 107 are received within guide slots formed in the end portions of upwardly extending arms 109 of a yoke 110 (Fig. 2) which is pivoted on an upwardly and rearwardly extending shaft or fulcrum pin 111 and which loosely embraces the sleeve 91. The shaft 111 is carried in a bracket 113 extending forwardly from the right-hand end portion of the intermediate section 3 of the casing. An arm 115 extending at right angles to the arms 109, and integral with one of the latter, is connected by means of a ball-and-socket joint 117 to an upper end portion of an arm 119 extending forwardly and upwardly through an opening in the front portion of the base section of the casing. The lower end of the arm 119 carries an eccentric strap 121 (Fig. 2) surrounding an eccentric 123 which is mounted on a horizontal shaft 125 journaled in a suitable support carried by the base section of the casing. The shaft 125 is parallel to the buffing roll shaft 31 and carries a fixed pulley 127 driven by a belt 129 from a pulley 131 on the countershaft 21. Thus, as the shaft 125 is rotated, the eccentric 123 mounted thereon rocks the arms 109 and, through the connections above described between the arms 109 and the shaft 31, imparts reciprocatory movement to that shaft. A guard 141 is provided to shield the portion of the arm 119 which lies outside the base section 1 of the casing, and a guard 143 is provided for partially surrounding the sleeve 91 to prevent an operator's fingers being trapped between the flange 93 and the adjacent bearing for the shaft 31 during the reciprocating movement of the shaft. The arrangement just described allows the shaft 31 to be oscillated without any substantial thrust being applied in a direction transversely of the shaft and thus reduces to a minimum the wear on the bearings supporting the shaft.

The top section 5 of the casing extends about half way across the intermediate section 3 of the casing from right to left of the machine and has a central portion 145 (Fig. 1) which extends somewhat higher than the remainder of this section of the casing. Secured by clamping screws 200 to faces 147 formed on a front wall (one at the left-hand and the other at the right-hand end portions thereof) of the top section 5 of the casing, are two brackets 149. The screws 200 extend through arcuate slots 201 which are formed in the brackets 149 to provide for limited adjustment of the brackets about a substantially horizontal axis extending forwardly and rearwardly of the machine. Each of the brackets 149, at a forward end portion thereof, carries a shank buffering tool 151 of the inflated disk type. Air for inflating the tools 151 is supplied through a flexible pipe under control of a valve 173, and if desired may be conveniently obtained by driving a compressor (not shown) from the shaft 125. The tools 151 are driven by belts 153 from pulleys

155 carried by a horizontal transversely extending shaft 157 which is journaled in bearings in the central portion 145 of the top section 5. The shaft 157 is provided with a pulley driven by belt 202 from the countershaft 21.

The pulleys 155 are secured to portions of the shaft 157 extending outwardly from side walls of the central portion 145 of the top section 5 of the casing. The belts 153 and pulleys 155 are guarded by means of inverted U-shaped guards 159 pivotally mounted at rear portions thereof on vertical studs 161 secured in bosses 163 in the top section 5 of the casing. In each of the walls designated by the reference numerals 165 and forming the sides of each inverted U-shaped guard 159, at forward end portions thereof, is a horizontal adjusting screw 167, an end of which engages a cylindrical surface 169 on an adjacent portion of the bracket 149 supporting the associated buffing tool 151. By adjustment of the screws 167 the positions of the guards 159 transversely of the brackets 149 may be adjusted. On adjustment of one or the other of the brackets 149 relatively to the top section 5 of the casing, as above referred to, the portion of the bracket in which the buffing tool is mounted will swing transversely of the machine, and the associated guard 159 will move about its pivot stud 161 with its bracket 149 to guard the belt drive 153 in any adjusted position of the bracket 149. A dust-collecting hood 203, carried by the bracket 149, is provided for each buffing tool 151 and is in communication, through a duct 175, with the main duct already mentioned.

It will be appreciated that the various shafts, pulleys and belt drives are at least substantially enclosed within the casing of the machine frame, or are guarded by means of the guards and hoods above described. There is thus little danger of injury to the operator by moving belts or rotating shafts or pulleys which, in prior machines, have often been dangerously exposed.

Having described our invention, what we claim 10 as new and desire to secure by Letters Patent of the United States is:

Mechanism for reciprocating a buffing roll shaft, comprising a ball bearing having an inner race and an outer race, the inner race of said ball bearing being secured to said shaft against relative axial movement, a pair of trunnion pins extending from the outer race of the ball bearing, a slide block pivotally mounted on each of said trunnion pins, a yoke embracing said outer race 15 and having a pair of guide slots in which said blocks respectively are slidably mounted, a fulcrum upon which said yoke is mounted for oscillatory movement, a driven shaft parallel to said buffing roll shaft, an eccentric on said driven 20 shaft, a connecting rod from said eccentric to said yoke, and a universal joint between the connecting rod and the yoke, whereby the yoke is oscillated to impart reciprocatory movement through the ball bearing to the shaft, said guide slots serving to avoid transmission into the bearing of the transverse component of movement of the yoke.

HAROLD ERNEST ELLIOTT.
LAWRENCE MAWBEY.
